UNITED STATES PATENT OFFICE.

CHARLES HEART, OF ALEXANDRIA, INDIANA, ASSIGNOR TO KEEFER-HEART IRON AND STEEL COMPANY, OF ALEXANDRIA, INDIANA, A CORPORATION.

SHEET-METAL RIM OR FELLY.

No. 853,452.

Specification of Letters Patent.

Patented May 14, 1907.

Application filed February 20, 1906. Serial No. 302,070.

To all whom it may concern:

Be it known that I, CHARLES HEART, a citizen of the United States, residing at Alexandria, in the county of Madison and State of Indiana, have invented certain new and useful Improvements in Sheet-Metal Rims or Fellyes, of which the following is a specification.

This invention relates to vehicle wheels, and particularly to the construction of the felly or rim of such wheels.

The objects of the invention are to provide a felly or rim, preferably constructed of sheet metal, which may be applied to wheels of usual construction, and over which a tire of the ordinary make may be applied with ease and facility.

A further object is the provision of means for preventing lateral movement of the tire on the periphery of the rim or felly, and also means are provided for bracing the spokes within the felly and strengthening the felly itself, against collapse.

The construction as hereinafter defined provides a felly which is cheap in first cost and durable, and one which combines strength with lightness of material.

The invention consists essentially in a hollow metallic felly comprising strengthening webs which also act to steady and prevent displacement of the ends of the spokes of the wheel, and means in conjunction with the tire of the wheel for preventing lateral movement of the tire.

In the accompanying drawings I have illustrated one example of the physical embodiment of my invention.

Figure 1 is a view showing a portion of the felly and fragments of spokes, the felly being broken away at the end of one spoke for convenience of illustration, and also showing the band which covers the joint of the two ends of the one piece felly. Fig. 2 is a transverse vertical sectional view of the felly at a spoke end. Fig. 3 is a top plan view of the tire, showing a portion of the same broken away to illustrate the flat sides of the wires for preventing the lateral movement of the tire, and another portion broken away on a lower plane to show the construction of the felly where the adjacent ends are joined together. Fig. 4 is a fragmentary sectional view at the joint of the felly illustrating how the end of the joint band is held under the tire.

The felly consists essentially of a sheet metal ring, as 1, preferably hollow and of one piece of metal, although if desirable the felly may be made of a plurality of pieces. As illustrated clearly in Fig. 3 the adjoining ends of the felly are turned back upon themselves, 55 and the flanges 2 and 3, which extend around three sides only of the felly are securely held between the bent ends 4 and 5 of the tubular joint band 6. In this manner a rigid and stable joint is secured and the felly is prevented from expanding under pressure.

A suitable number of openings are provided at the inner side of the felly for the reception of the ends of the spokes 7, said spokes being provided with a thimble 8 formed with a shoulder 9. The edges 11 of the wall around the spoke opening in the felly are turned in and the shoulder 9 finds a seat against this turned in circular wall or edge around the opening in the felly. In cross section the 75 felly or tubular ring 1 is approximately of a U-shape having its outer ends bent over toward each other, but a space along the central line of the felly is provided between the two flanges 12 and 12' (see Fig. 2). This space 80 between the two flanges is partly filled by the wide rib or projecting ring 13 formed centrally on the exterior periphery of a second, interior tube 14, which is present to reinforce and strengthen the tubular felly 85 proper. The interior tube 14 is also approximately U-shaped in cross section, but located in reverse position to the felly proper, and is provided with annular webs 15 and 16, between which an annular channel is formed, 90 and into this channel the thimbles 8 of the spokes project. These webs serve not only to strengthen the felly when under radial pressure, but also brace and steady the ends of the spokes, as will be readily understood. 95 As is the case with the tubular felly the interior tube is also constructed of one piece, and as illustrated in Fig. 3 a metallic block or piece 17 is interposed between the ends of the side walls of the tube and also the webs of the tube, the block being located at the joint in the exterior felly tube.

As before stated the space between the two flanges 12 and 12' of the outer tube is partially occupied by the wide ring 13 on the inner tube, and as indicated in Fig. 3 two channels or grooves are formed in the periphery of the felly, one at either side of the cen-

tral ring 13 and bounded on their outer sides by the flanges 12 and 12'. Within these channels I locate the rings 18 and 19. The channels provide a seat for the rings which are semicircular in cross section, having their flat faces flush with the periphery of the exterior felly and the ring 13, of the interior tube. The tire 20 of usual pattern is pressed on the flat surfaces.

10 At the joint in the felly the two flanges 12 and 12' are cut away to provide a seat for the flat ends 21 of the joint band, and the ends 21 extend inwardly to a line with the flanges 12 and 12', thus providing a smooth continuous 15 surface on the periphery of the felly at its joint.

10 The two rings 18 and 19 fit comparatively loosely in their channels or seats and are capable of turning therein, as for instance, 20 if from any cause the tire should tend to shift or slide sidewise on the periphery of the felly, the movement would cause a rotative motion to be imparted to the rings, slight of course, but sufficient to turn one of the 25 corners or points or edges 18' or 19', to present a sharp edge to the inner surface of the tire and prevent the lateral movement, and the greater the pressure, the stronger the 30 resistance which will be presented by the sharp edge of the rings to the tire.

35 From the above description taken in connection with the drawings it becomes obvious that I have produced a wheel felly which fulfils all the objects set forth as the purpose of my invention.

Having thus fully described my invention, what I claim as new and desire to secure by Letters Patent is:

1. The combination in a wheel and with 40 the spokes thereof of a hollow metallic felly having openings therein to receive the spokes, annular channels in the periphery of the felly and rings semi-circular in cross section seated in said channels; and a tire surrounding said felly and adapted to be engaged by 45 the edges of said rings.

2. The combination in a wheel and with the spokes thereof, of a felly, tubular in cross section and provided with openings to re-

ceive said spokes, an inner tube within the 50 felly tube, said inner tube comprising means for bracing the ends of the spokes, substantially as described.

3. A felly comprising a tubular metallic annular shell, an inner shell, and annular 55 webs formed in said inner shell.

4. A felly comprising a tubular metallic annular shell having a continuous opening in its periphery, an inner shell having a projecting ring located in said opening, rings 60 semi-circular in cross section seated on the inner shell, and a tire surrounding the tire and bearing on said felly, projecting ring and rings semi-circular in cross section, for the purpose set forth. 65

5. A felly comprising a tubular metallic annular shell, an inner shell having annular webs formed integral therewith, means for forming a joint on the outer shell, and a filler block located between the adjoining ends of 70 the walls of the inner shell and the webs thereof.

6. The combination in a wheel and with the spokes thereof, of an outer tubular metallic shell having a continuous opening in 75 its periphery, an inner shell having a ring projecting through said opening but leaving a space at each side thereof, a ring, semi-circular in cross section located in each said space, and a tire surrounding the felly and 80 adapted to be engaged by said rings; the adjoining ends of said outer tube or shell being turned back upon themselves and inclosed by a flanged joint piece, substantially as described. 85

7. The combination in a wheel and with the spokes thereof, of an outer metallic tubular felly shell, having openings therein to receive the spokes, an inner tubular shell provided with annular webs forming braces for 90 the ends of the spokes, and a tire surrounding said felly, substantially as described.

In testimony whereof I affix my signature in presence of two witnesses,

CHARLES HEART.
